UNITED STATES PATENT OFFICE.

JOHN HAYS HAMMOND, JR., OF GLOUCESTER, MASSACHUSETTS.

EXPRESSION DEVICE.

Application filed May 26, 1925, Serial No. 32,878. Renewed February 27, 1929.

This invention relates to improvements in music modulators and more particularly to the control of tone shading and musical dynamics.

- 5 The present invention has particular reference to a system of tone shading for musical instruments of the percussive type, and provides improved control of musical dynamics in the different parts of the musical scale. It may be employed, however, with 10 equal advantage in connection with any other type of musical instrument where it may be desired to control the tone shadings of a musical scale.
- 15 The principal object of the invention is to provide means for modulating the volume of sound produced by a musical instrument differently in different parts of the scale.

A feature of the invention relates to the 20 provision of a plurality of modulating means operable synchronously and controlled by a plurality of control devices.

Other objects will appear from the following description taken in connection with the 25 accompanying drawings in which—

Figure 1 is a plan view and Figure 2, is a front elevation of a musical instrument of the automatic playing type.

Figure 3 is a section taken on the line 30 3—3 of Figure 1.

Figure 4 is a sectional view in detail of the operating mechanism of Figure 3, and

Figure 5 is a sectional view in detail of the control valve of Figure 3.

35 Like reference characters refer to like parts in the several figures of the drawing.

In the following description and claims, parts will be identified by specific names for convenience of expression, but they are intended to be as generic in their application to similar parts or equivalent construction as the art will permit.

Referring to Figures 1, 2 and 3 of the drawings, there is shown for the purpose of 45 illustrating one form of the invention, a grand piano of the automatic player type comprising a casing 10 supported on suitable feet in a conventional manner and having positioned therein a plurality of strings such as 11, 12 and 13, tuned to the notes of the musical chromatic scale. The strings 11 of the right-hand portion of Figure 3 are assumed to be tuned to the lower notes of the scale and the strings 13 in the left-hand end

to the upper notes of the scale, and the intermediate strings such as 12, tuned to the intermediate notes of the scale. The strings 11, 12 and 13 are stretched upon a conventional frame 14 and are preferably arranged in a single plane, as for example, in the case 50 illustrated, a horizontal plane.

For each note of the musical scale there is provided a hammer, such as 15, arranged to impact with, and to set into vibration, the strings tuned to the respective note, and actuated by means of a piano action 16 and a key 17 in a conventional manner. The keys such as 17 are arranged in a manual 55 18 and may be operated manually in a well-known manner to produce musical sound.

For operating the piano actions 16 automatically in order to produce music automatically, there is provided for each of the actions 16, an accordion pneumatic 19, each pneumatic including a collapsible bellows 70 arranged to impart movement to the respective piano action upon the collapse of the bellows, in a manner well known in the automatic player art. The pneumatics corresponding to the lower notes of the musical 75 scale are connected to a bass stack or conducting pipe 20, and similarly the striking pneumatics corresponding to the upper notes of the musical scale are connected to a similar treble stack 21.

The bass stack 20 and the treble stack 21 communicate respectively with a bass modulating mechanism 22 and a treble modulating mechanism 23 which may be of any well known suitable construction, and which serves to control the suction in 80 the stacks to which they are connected. The modulating mechanisms 22, 23 are in communication with a suction feed chamber 24 and by way of a suction feed pipe 25 to the interior of a suction regulating bellows 26. The suction regulating bellows 26 is positioned within a bracket 30 rigidly secured to a casing 31, forming a suction reservoir 85 chamber 32. With no suction within it, the bellows 26 is held in distended position by means of a plurality of springs 33 fastened thereto, the other ends of the springs being connected to the fixed bracket 30. A valve 90 port 34 provides for communication between the interior of the bellows 26 and the chamber 32 and is controlled by a valve member 35 mounted on a valve stem 36, one end of which is secured to the moving element of

the bellows 26, the other end of the stem being slidably mounted in a bracket 37 carried on the base of the casing 31 and positioned within the chamber 32. The chamber 32 is in communication by means of a pipe 38 with a source of suction, such as a blower 39, operated by a suitable motor 40 of conventional construction. The bellows 26 thus controls the valve port 34 and regulates the amount of suction in the pipe 25, to a predetermined degree. The predetermined suction in the pipe 25 may be varied by changing the tension on the springs 33.

For automatically operating the instrument there is provided a tracker bar 50 having a plurality of holes arranged in alignment. Spaced apart from the tracker bar are two roll holding devices 51 and 52 upon which there may be mounted roll spools 53, 54 for a paper roll such as 55, which is perforated in a predetermined manner in accordance with the music to be played. The perforations in the roll 55 are such that when a note in the musical scale is to be sounded, a perforation in the roll is brought into registry with the tracker bar hole which has been assigned to the respective note of the musical scale. Each of the note holes of the tracker bar 50 communicates with a pipe such as 56 and thus to the respective striking pneumatic so that when the roll uncovers the perforation therein, the striking pneumatic 19 is actuated to operate the hammer action and thus to sound the respective note. Additional perforations are provided near each edge of the paper roll 55 for the control of expression. The arrangement of holes may be in any desired manner, that shown being such that the note holes are intermediate the modulating holes. The bass expression holes, preferably positioned near the left hand edge of the tracker bar 50 as seen in Figure 2, communicate by means of pipes 57 with the bass modulating mechanism 22 and the treble expression holes preferably near the right hand edge of the tracker bar communicate by means of pipes 58 with the treble modulating mechanism 23. Thus the expression mechanisms 22 and 23 may be automatically controlled in a predetermined manner according to the perforations in the paper roll. Expression mechanisms 22 and 23 are of a form well-known in the art and may be of the type set forth in Patents 1,444,832 and 1,359,040 to J. H. Dickinson. The particular construction, however, forms no part of the present invention and will not be set forth in detail herein. It will be seen that the suction in the bass stack 20 is varied in accordance with the expression to be imparted to the bass notes of the music, while the suction in the treble stack 21 varies in accordance with the expression imparted to the treble notes of the music. Such variations in suction in the

stacks are caused to control independently the musical tones emitted from the instrument according to the relation of the tones in the musical scale, by means automatically controlled and which will now be described in detail.

A conducting passage 60 of relatively small cross sectional area extends from the bass stack 20 to an accordion pneumatic 61 which includes a conventional collapsible bellows. The bellows of the pneumatic 61 is operatively connected by means of a shaft 62 to one end of a balanced lever 63, which is pivotally mounted upon a bracket 64 secured to the frame of the piano. The other end of the lever 63 is pivotally connected to a primary slide valve member 65 (see Figure 5) which reciprocates in a valve casing 66 and which is provided with a valve port 67 in an intermediate portion thereof and with two oppositely disposed passages 68, 69. The valve port 67 is in communication by way of a valve inlet chamber 70 with an ancillary feed pipe 71 communicating through a cross feed pipe 72 with the suction feed pipe 25. A secondary slide valve member 73 is positioned immediately adjacent the primary slide valve member 65 and is arranged to reciprocate independently thereof and within the valve casing 66. The secondary slide valve member 73 is provided with two spaced ports 74, 75 separated by a partition 76. The normal position of the slide valve members 65 and 73 is as shown in Figure 5 of the drawing with the primary slide valve port 67 opposite to and closed by the partition 76 of the secondary slide valve member. The passage 68 is at atmospheric pressure and is normally in communication with the upper secondary valve port 74. The lower passage 69 is also at atmospheric pressure and is normally in communication with the lower secondary valve port 75. The upper valve port 74 communicates with a conducting pipe 76' and thus in turn with the upper portion 77 of a double bellows 78, the lower portion 79 of which is similarly in communication by way of a conducting pipe 80 with the lower secondary valve port 75. The bracket 64 is provided with an offset lug or ear 81 through which is threaded an adjusting thumb screw 82. A retractile spring 83 is fastened between an end of the adjusting thumb screw 82 and a movable portion of the pivoted lever 63 for restoring the lever 63 and the primary slide member 65 to a predetermined position. The tension of the spring 83 may be varied as desired by regulating the thumb screw 82. The double bellows 78 is rigidly mounted on the bracket 64 near the bass end of the piano and includes a central member or lever 90, the position of which is determined by the conjoint action of the two halves 77, 79 of the bellows. The outer end of the lever 90 is

connected by means of a link 91 to the secondary slide valve member 73.

A similar mechanism for the treble end of the piano is provided, comprising a conducting passage 160 of relatively small cross sectional area which is led from the treble stack 21 to an accordion pneumatic 161 which includes a conventional collapsible bellows. The bellows of the pneumatic 161 is operatively connected by means of a shaft 162 to one end of a balanced lever 163, which is pivotally mounted upon a bracket 164 secured to the frame of the piano. The other end of the lever 163 is pivotally connected to a primary slide valve member 165 corresponding to the primary slide valve member 65 previously described and illustrated in Figure 5 which reciprocates in a valve casing 166 and which is provided with a valve port 67 in an intermediate portion thereof and with two oppositely disposed passages 68, 69, as illustrated in Figure 5. The valve port 67 is in communication by way of a valve inlet chamber 70 with the ancillary feed pipe 71 communicating through the cross feed pipe 72 with the suction feed pipe 25. The construction of the treble casing 166 is in all respects similar to that of the bass casing 66 and the description already given will, it is thought, suffice for both. The upper valve port 74 communicates with a conducting pipe 176 and thus to the upper portion 177 of a double bellows 178, the lower portion 179 of which is similarly in communication by way of a conducting pipe 180 with the lower secondary valve port 75. The bracket 164 is provided with an offset lug or ear 181 having an adjusting thumb screw 182. A retractile spring 183 is fastened between an end of the adjusting thumb screw 182 and a movable portion of the pivoted lever 163 for restoring the lever 163 and the primary slide member 164 associated therewith to predetermined position. The tension of the spring 183 may be varied as desired by regulating the thumb screw 182. The double bellows 178 is rigidly mounted on the bracket 164 near the treble end of the piano and includes a central member or lever 190, the position of which is determined by the conjoint action of the two halves 177, 179 of the bellows. The outer end of the lever 190 is connected by means of a link 191 to the secondary slide valve member 173.

Within the casing 10 of the piano there is provided a casing 140 formed of substantially sound proof material and comprising an upper wall 141 arranged in a plane parallel to the strings 11, 12, 13, a lower wall 142 in a plane parallel thereto and oppositely disposed of the strings, and intermediate boundary walls 143, 144. The upper and lower walls 141, 142 are provided with controllable apertures and in the plane of the upper wall 141, there is provided a plurality of tone modulators including closures 145, 146, 147, each pivoted upon its longitudinal axis in the plane of the wall 141 so as to rotate with respect thereto. Each closure is provided with a lug such as 148 offset with respect to the axial mounting of the respective closure and pivotally connected by means of a link 149 to an upper operating floating arm or lever 150. Similarly in the plane of the lower wall 142 there is provided a plurality of tone modulators including closures 151, 152, 153, each pivoted upon its longitudinal axes in the plane of the wall 142 so as to rotate with respect thereto. Each closure is provided with a lug such as 148 offset with respect to the pivotal mounting of the respective closure and pivotally connected by means of a link 149 to a lower operating floating arm or lever 154. The operating arms 150 and 154 extend normally in substantially horizontal planes outwardly of the planes of the walls 141, 142. The bass ends of the arms are pivotally connected to a vertical operating shaft 155 which is mounted in bearings in the walls 141, 142 so as to reciprocate vertically and the lower end of the shaft 155 is connected by means of a link 156 to the outer end of the lever 90 of the bass bellows 78. Similarly the treble ends of the rods 150 and 154 are pivotally connected to a vertical operating shaft 157 which is mounted in bearings in the walls 141, 142 so as to reciprocate vertically and the lower end of the shaft 157 is connected by means of a link 100 to the outer end of the lever 190 of the treble bellows.

When the lever 90 of the bass bellows 78 is in its uppermost position so that the shaft 155 and the bass ends of the arms 150 and 154 are in the extreme raised position the closures 147 and 153 approximate thereto are in their closed positions. As the double bellows is actuated to lower the respective vertical shaft the closures become more widely opened, the open position being indicated at the treble end of Figure 3 wherein the double bellows 178 is shown in its actuated position with the lever 190 and the shaft 157 of the treble end of the instrument in lowered position.

In operation a paper strip 55 having perforations corresponding to music is placed upon the roll holders and the roll spools 53, 54 are rotated so as to bring successive parts of the paper strip into registry with the holes of the tracker bar 50. Certain of the holes control the suction in the groups of tracker bar tubes 57-58 so as to actuate the modulators 22, 23 respectively, and thus to modify the suction in the stacks 20, 21. By changing the amount of suction in the two stacks the proper degree of emphasis can be given to the music as may be desired to reproduce the playing of an artist. It will

be noted that the treble modulating device 23 is controlled in accordance with the expression to be given to the notes to be played at the treble end of the musical scale, while the bass modulating mechanism 22 is controlled in accordance with the expression to be given to the notes at the bass end of the musical scale and that the two modulating mechanisms 22 and 23 may be independently operated to cause variations in the amount of suction in the stacks 21 and 20. The variations in suction in the treble stack 21 are communicated to the pneumatic 161 thus causing this pneumatic to take up a position depending upon the amount of suction in the stack 21. The normal position of the pneumatic 161 and the lever 163 associated therewith may be determined by suitable adjustment of the retractile spring 183 and the lever 163 will take up a position depending upon the strength of suction in the stack 21 relative to the tension on the spring 183. As the lever 163 moves in a clockwise direction the primary valve member 165 is moved downwardly thus connecting the suction pipe 71 to the pipe 180 and collapsing the lower portion 179 of the treble bellows 178 to move the shaft 157 downwardly, until the secondary valve member 173 brings the partition 76 into registry with the valve port 67, thus shutting off the suction from the pipe 71. It is evident therefore that the lever 190 will follow the motion of the arm 163 and that the position of the lever 190 and the rod 157 operatively connected therewith is determined by the strength of suction in the stack 21. Similarly the position of the bass rod 155 is determined by mechanism, which has hereinbefore been described in detail, by the strength of suction in the bass stack 20 and therefore depending upon the strength with which the notes at the bass end of the instrument will be struck. Thus the ends of the rods 150 and 152 will take up positions depending upon the strength with which the notes at the respective ends of the instrument are being struck and grading off from one end to the other.

Thus the volume of sound emitted from the instrument at different parts thereof is modulated uniformly with respect to the emphasis being given to the corresponding notes of the instrument and producing particularly attractive tone shading and novel musical effects.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

45 What I claim is:

1. In a musical instrument of the percussive type, the combination with strings for producing musical sounds, of a casing having apertures, a plurality of closures for each of said apertures, said casing and closures being formed of a substantially sound-proof material, and means for actuating the closures of each group to a different degree with respect to the remaining closures of the respective group. 75

2. In a musical instrument of the percussive type, the combination with strings for producing notes of the musical scale, of a casing having apertures, a plurality of closures for each of said apertures and arranged in a determined relation with respect to said strings, said casing and closures being formed of a substantially sound proof material, means for variably actuating said strings to produce musical sound and means for variably actuating the closures of each group to a different degree with respect to the remaining closures of the respective group and proportionally to the variations in actuation of said strings. 90

3. In a musical instrument, the combination with tuned strings, hammers positioned to make striking contact with said strings to produce musical sounds, of a casing surrounding said strings and hammers, said casing having apertures, a plurality of closures for each of said apertures, and operating members for actuating the closures of each group to a different degree with respect to the remaining closures of the respective group. 100

4. In a musical instrument, a plurality of tuned strings for producing musical sounds arranged in the order of their sequence in the musical scale, a casing having apertures, a plurality of closures for each of said apertures, said apertured casing surrounding said strings, a floating lever for adjustably positioning the closures to vary the effective emission of sound from the casing, a shaft for each end of said lever and pivotally connected thereto, and means for independently operating the shafts. 110

5. In a musical instrument, a plurality of tuned strings arranged in the order of their sequence in the musical scale, a casing enclosing said strings and having apertures for the control of the emission of sound therefrom, a closure for one of said casing apertures positioned proximate to the treble strings, an additional closure for said aperture proximate to the bass strings, a percussive action for each of the notes of the musical scale for causing vibration of the strings tuned to the respective note, means for actuating said percussive mechanism with different degrees of force, means for actuating said treble closure to a degree proportional to the force of actuation applied to the treble percussive means, and means 130

for actuating said bass closure to a degree proportional to the force of actuation applied to the bass percussive means.

6. In a musical instrument, a plurality of tuned strings arranged in the order of their sequence in the musical scale, a substantially soundproof casing enclosing said strings and having apertures for the emission of sound therefrom, a plurality of closures for each 10 of said casing apertures positioned proximate to the treble strings, the intermediate strings and the bass strings respectively, a percussive action for each of the notes of the musical scale for causing vibration of the 15 strings tuned to the respective note, means arranged for actuation of said percussive mechanism with different degrees of force, means for opening each of said closures of each group to a different degree proportional 20 to the force of actuation applied to the percussive means associated with the part of the musical scale with which the respective closure is associated.

7. In a musical instrument of the percus-

sive type, the combination with tuned elements for producing musical sounds by percussion, of a casing having apertures, a plurality of closures for each of said apertures, and means for actuating the closures to a different degree with respect to the remaining closures of the respective group.

8. In a musical instrument of the percussive type, the combination with automatic roll playing mechanism for actuating said instrument to produce music, of a casing having apertures, a plurality of closures for each of said apertures arranged in a determined relation with respect to the musical scale, means for modifying the amplitudes of musical sound, and means controlled by 40 said modifying means for variably actuating the closures of each group to a different degree with respect to the remaining closures of the respective group.

Signed at New York city, in the county 45 of New York and State of New York this 25th day of May A. D. 1925.

JOHN HAYS HAMMOND, JR.
